UNITED STATES PATENT OFFICE.

RUDOLPH M. HUNTER, OF PHILADELPHIA, PENNSYLVANIA.

REFRIGERATING APPARATUS.

1,015,957.

Specification of Letters Patent.

Patented Jan. 30, 1912.

Application filed December 31, 1897. Serial No. 664,808.

To all whom it may concern:

Be it known that I, RUDOLPH M. HUNTER, of the city and county of Philadelphia, State of Pennsylvania, have invented an Improvement in Refrigerating Apparatus, of which the following is a specification.

My invention has reference to refrigerating apparatus and consists of certain improvements which are fully set forth in the following specification and shown in the accompanying drawings which form a part thereof.

This application has special reference to means for varying the temperature of compartments and more particularly for cooling or refrigerating distant compartments or rooms of buildings. In the preferred form of my invention I utilize the heating apparatus employed in cold weather as the means of extracting the heat from the rooms or varying the temperature of the compartments in summer.

In large buildings, such as hotels and office buildings, a steam heating plant is employed to properly heat the buildings in the winter, but this remains idle in summer. I propose utilizing the heating system, preferably including the radiators, as the means of cooling the rooms by passing through them governed quantities of cold brine, air or other fluid rendered cold by suitable refrigerating processes at a considerable distance from the rooms to be cooled. When air is used part or all of it may be allowed 35 to escape into the room or compartment. In carrying out this part of my invention I provide the steam supply pipe with a valve by which the connection with the steam boilers or exhaust of the engine can be cut off. 40 I further provide a brine tank adapted to receive the water or media returned from the system of pipes and radiators and also to act as a source of supply for a pump which forces the cold brine or media upward 45 through the system of pipes and radiators. The brine tank is further combined with suitable refrigerating apparatus for cooling the brine or media to a low temperature. In this manner the heating system of pipes 50 is utilized in warm weather as the immediate holder of the cooling media and permitting its full circulation in every direction, thus performing the dual function of both heating and cooling. The cost of equipment 55 is thus low, and in the case of large hotels

which already are supplied with refrigerating plant the same may be readily combined with the heating system by the proper connections and valves. Any suitable means for cooling the brine or circulating media 60 may be employed, but where the apparatus is of considerable size the compression system would be preferable.

While I have above referred to cooling rooms in a building, I may equally employ 65 my invention in connection with railway cars whether for passenger or freight. Where heating pipes for steam leading from the engine are employed to heat the cars they may be utilized, as above explained 70 with regard to the heating system in buildings, for cooling the cars, as will be more fully explained hereinafter. Now while my invention is adapted to be a system for alternately heating and cooling distant rooms 75 or compartments it is not confined to a system which shall be used for heating since the invention may be used wholly for cooling or refrigeration where heating is not required.

My invention will be better understood by 80 reference to the accompanying drawings, in which:

Figure 1 is a side elevation of a railway train, part in section showing my improvements applied thereto; Fig. 2 is a diagram 85 showing a different type of refrigerating apparatus adapted for use with my improvements; and Fig. 3 is a sectional elevation of a building showing my invention applied thereto.

Referring first, to the construction shown in Fig. 1 I have illustrated a train of cars especially adapted to the transportation of perishable goods. In this figure A represents the locomotive, the rear portion of the 95 tender alone being shown. B is the car containing the refrigerating apparatus proper and C one of the cars in which the goods to be transported are to be placed. The car C consists of compartments closed against the outside atmosphere and provided with coils G through which the media to vary the temperature is passed. Each car is also provided with a longitudinal supply pipe F and the return pipe H with which the respective 100 ends of the coil G are connected. Suitable valves l g or either of them may be employed in the terminals of the coil to control the flow of the media to be passed through the coil. The ends of the pipes H 110

and F terminate in flexible couplings I such as are commonly employed on the Westinghouse air brake system. When the cars C are intended to transport perishable merchandise such as meats or vegetables it is made like a box-car having tight doors and the media which is passed through the coil G is a refrigerant such as a cold brine. If the car C is intended for passenger service, 10 then the coils G may be employed to heat the car in winter and cool it in summer by passing steam through it in the winter time and a refrigerant such as cold brine or cold air in summer time. This would largely obviate 15 the great objection to opening the windows and doors of trains in the summer usually made necessary by the excessive heat. The particular character of the car C or compartment on wheels is therefore immaterial and while in the fullest carrying out 20 of my invention a very large variation of temperature to suit the requirements of winter or summer may be secured, nevertheless it is not necessary to employ my apparatus 25 for heating purposes at all.

Referring now to the car B we have therein a tank D adapted to contain brine. A pipe i connects with the said tank and terminates in a flexible coupling adapted to 30 unite with the coupling of the pipe H at I so that the return of the brine to the tank D after cooling the compartment C is secured. A discharge pipe e leads from the brine tank near the bottom and terminates 35 in a coupling adapted to connect with the flexible coupling at I' leading from the supply pipe F of the car C. A pump E is arranged in the car B to circulate brine through pipe e so that cold brine is positively forced through the pipe F. The amount of the cold brine which circulates 40 through any one of the coils G in the cars C may be controlled by either or both of the valves g l. The brine tank D is provided 45 with a cooling coil J of any suitable construction the upper end of which leads to a condenser L, and the lower end of which connects with a compressor K also arranged within the car B. The compressor K compresses 50 the gas such as anhydrosulfurous acid, which then enters the condenser L under pressure and is liquefied. From there it is forced over into the coil J of the tank D and vaporized, the vapor being drawn off again by the compressor as is well known. In this manner the brine or whatever circulating media may be used and contained 55 in the tank D is kept in a cold condition so that the warmer media returned by the pipe i is again chilled or cooled before being forced through the various cars by the pump E.

The condenser L in the car B requires a constant change of water to condense the anhydrosulfurous acid, and this is secured

by a water pipe m including a pump M for forcing the water into the condenser. The pipe m communicates with a water pipe m' leading from the tank O of the tender of the locomotive A with which it is connected by a flexible coupling N. In this manner cold water may be forced by the pump M into the condenser and the warm water allowed to overflow by a pipe n and discharge through a flexible coupling N' into the upper part of the tank O of the tender. When the coils G are intended for heating purposes it is then necessary to circulate steam through the pipes F H, and this I accomplish in the following manner. A pipe P on the locomotive leads from the boiler and connects by a suitable coupling with pipe P' on the car B from which steam may be supplied for operating the pumps and compressor. Pipe P² connects the pipe p¹ 85 with the pipe e and is provided with a valve. By opening the valve in this pipe P² steam may pass into the pipe F on the car C and may be permitted to escape after passing through the coils G, 90 or more preferably returned by the pipe i to the tank D in which a partial vacuum is maintained by the pump E so that the steam circulates at a pressure below that of the atmosphere on the principle of the well known vacuum system. In this case a valve d' is arranged in the pipe e and between the connection of the pipe P² and the pump and of such construction as to shut off the pump E from the pipe F and open 10 its discharge to the atmosphere through pipe V.

In place of using anhydrosulfurous acid as the media for producing the cooling of the brine or other circulating media, I may use ammonia or any other highly volatile substance. In lieu of the particular apparatus for refrigerating shown in the compartment B using the compressor K, I may employ an ammonia refrigerator operated by the application of heat, such for instance as shown in Fig. 2. In this case the tank D containing the brine is connected with the pipes i and e leading to the couplings I as before, and including the circulating pump similar to that previously described.

R and R' are two generators and consist of closed tanks containing strong solutions of ammonia. They are each provided with coils connecting with steam and water supply. When steam is admitted to the coils of one of these generators water is admitted to the coil of the other and vice versa, so that one generator drives off the ammonia by heat, while the other generator acts as an absorber and causes the ammoniacal gas to be absorbed. The upright pipes from those generators connect with a condenser L which at its discharge end connects with the refrigerator coil J in the brine tank D. The

other end of the refrigerating coil connects by suitable pipes *j* with the respective pipes leading to the two generators. The pipes leading to and from the generators are provided with valves *r r' c c'*.

In the operation, when the ammonia is being generated in generator R the valve *r'* is closed and valve *r* open, and likewise valve *c* is closed and valve *c'* open. The ammonia is condensed in the condenser L and is allowed to evaporate or expand in the coil J. The expanded ammonia passes by pipe *j* through valve *c'* and into the absorber R'. When the ammonia is approximately all driven off from the water in the generator R, the valves which were formerly open are then closed and the valves which were formerly closed are then opened and now the generator R' produces the ammonia gas while the generator R becomes the absorber. The steam and water for operating this system may be received from the locomotive. If desired a separate water tank may be carried in car B.

When my improvements are applied to buildings, such as large office buildings where there are large numbers of rooms or apartments separated from each other, I provide preferably supply and return pipes F H leading to the distant parts of the buildings as indicated in Fig. 3. There may be as many of these return and supply pipes as the nature of the building may require, but they all lead to one place where the refrigerating and heating apparatus is located, usually in the basement.

More specifically referring to Fig. 3, C' represent different rooms and B' the room or chamber in the basement for the heating and refrigerating apparatus. F and H are supply and return pipes corresponding to the usual pipes in steam heating apparatus. G are the radiators or heating coils arranged in each of the rooms and connected through valves, *g*, *l* respectively with the supply pipe F and return pipe H so that the various heaters or coils G are arranged in parallel. W is the usual steam pipe and may be provided with a valve *k* to control the supply of steam or shut it off. The pipe W may lead from the exhaust pipe of the engine or from the boiler as preferred as is customary. In winter time the steam is caused to circulate through pipe F coils G and return pipe H. Furthermore, in the most improved types of steam heating apparatus the circulation of the steam is induced by the production and maintenance of a partial vacuum at the return end of the system, and for this purpose a tank T is provided connecting with the return pipe H by the pipe S which may be furnished with a valve *w*. A partial vacuum may be maintained in the tank T by pump E connected with the tank T by providing a pipe Q

which may have a valve *p* to shut off communication of the tank with the pump when the latter is circulating the cooling media. The discharge side of the pump may lead by a pipe *e* through a valve *d* to the escape pipe U. The pipe *e* is shown as a continuation of the supply pipe F but may be separated from it by closing a valve *h*. By operating the pump E during the use of the apparatus as a steam heating system the steam is caused to flow at a pressure at or below that of the atmosphere through pipe F, coils G and return pipe H and the water of condensation received in the tank T may be forced by a boiler feed pump *t* into the boiler. In the warm summer time when it is desired to cool the place I close the valves *h*, *w*, *d* and *p* and open the valve *b* in the return pipe leading at *i* into the brine tank D. The valve *h* is also opened to form communication between the discharge of the pump E and the supply pipe F. The suction of the pump is also connected to the lower part of the tank D, which connection may or may not be provided with a valve as desired. The tank D is provided with the refrigerating coil J as in the case of Fig. 1, which coil is employed to cool the circulating media in the tank D. L is the condenser having its coil connected at one end with the coil J and at the other end with the compressor K, the suction side of the compressor being connected with a pipe at the lower end of the coil J. P is a steam pipe for supplying steam to the steam engine of the compressor. The condenser L may be supplied with water by the water main *m* and which may be extended as at *m'* to supply water to the brine tank D when necessary. A discharge pipe *n* may be employed to permit the water to circulate through the condenser L.

The operation of the apparatus to cool the rooms is precisely the same as that described in connection with Fig. 1 where the different cars correspond to the different rooms. In this case the brine in its cold condition is forced upward by the pump E through the pipes *e* F and allowed to pass under any desired degree of circulation through the independent coils G, the circulation being controlled by either the valves *g* or *l* or both. The escaping brine passes by the return pipe H into the tank D and after being again cooled is once more circulated. If desired the upper ends of the radiators G may be connected by a valved pipe *l'* with the return pipe H so that when employing the circulating brine as a cooling media the valve *l* may be closed and *l'* may be open to insure the complete circulation of the brine throughout the entire radiator when made of the form usually found in steam heating apparatus for buildings. This precaution would not be necessary where ordinary

heating coils such as used in factories are employed as those coils are of substantially the construction shown in G in Fig. 1.

While I have described the circulation of 5 brine as a media on account of the intense temperature which can be given to it without freezing I do not confine myself to a liquid, for instead I may simply circulate air, causing it to pass through the tank D to 10 secure the necessary low temperature before being passed through the supply pipe F and the radiators G. Where air is employed it is not essential that the air shall be circulated over and over again as no harmful effects 15 will result from permitting the air to escape from the pipes into the compartments or rooms C' through suitable outlets G'. In this case the air would be permitted to enter the tank D by a valved pipe D' which may 20 communicate with the outside of the building to secure fresh air. The air upon passing through the tank D becomes greatly reduced in temperature and is then forced upward into the supply pipe F into the rooms 25 or compartments C' by the pump or any suitable blower. If desired the cold air may first be required to pass through the coils G to use them as refrigerating coils to cool the circulating air and may then escape 30 through a valved orifice G². I have shown this valve in dotted lines as opening from the upper end of the coils G, but it is self evident that its particular connection with 35 the coils is immaterial as I do not confine myself to the minor details. In this manner the cooling effect of the coils is maintained while at the same time permitting the actual escape of part or all of the air into the room. It is also evident that by properly manipulating 40 the valve the air may be circulated through the coils G employing the supply and return mains F H and at the same time permit the reasonable amount of the cooling air to escape from the valved orifices G' or 45 G² into the room to secure fresh air, and such loss from the circulating system to be regained by the valved pipe D'. In this manner I maintain the great cooling effect of the radiators while at the same time permitting 50 a large part of the cooling media to escape into the room to impart the necessary freshness to the air where there is not a sufficient draft or natural means to secure the proper supply.

55 It is evident that by a construction of apparatus and system of operation herein set out I may provide the large office buildings and others needing it with means for securing exceptionally wide ranges of temperature 60 in the independent compartments, being able to secure the highest temperature possible in the winter and the coolest temperature advisable in the summer, and this too by the employment of substantially a 65 single organization of piping both for heat-

ing and cooling. It will be evident that by very slight modification and additions I can at a small expense increase the capacity of any steam heating plant in use in connection with such buildings to vary the temperature of the compartments, securing the same comfort in exceedingly hot weather that can be obtained in the coolest weather. In other words, by my improvements I can give to the present piping and radiators an 70 75 enormously increased capacity for varying the limits of temperature in the compartments.

I do not confine myself to the details of construction herein disclosed as they may be 80 modified and varied in numerous ways without departing from the principles of my invention.

Having now described my invention what I claim as new and desire to secure by Letters Patent, is:

1. The combination of two or more compartments, a radiating device in each compartment, a supply pipe and a return pipe leading to the several compartments and 90 connected with the radiating devices, a tank communicating with the return pipe, a pump between the tank and supply pipe adapted to be used to reduce the pressure in the return pipe, a valved steam pipe 95 connecting with the supply pipe, and means for permitting the pump to discharge outside of the supply pipe.

2. The combination of a compartment on wheels provided with temperature varying 100 coils and supply and return pipes extending the length of said vehicle, and a second compartment on wheels provided with a tank, a pump between the tank and supply pipe adapted to be used to reduce the pressure in the return line, and said pump and tank being respectively connected with the supply and return pipes by flexible pipe couplings between the two compartments on wheels, a valve pipe for supplying steam to 110 the supply pipe and adapted for connection with the tender of a locomotive, and a valve orifice to permit the pump to discharge to the atmosphere.

3. Apparatus for producing a great variation in temperature in a number of independent closed compartments, comprising supply and return pipes, combined with a vacuum pump, means for causing the pump to create a partial vacuum in the return 120 pipe or to supply pressure to the supply pipe for causing a circulating vaporous or fluid medium under widely different conditions of temperature to flow through the supply and return pipes to and from the several compartments without mixing with the air of said compartments, valved pipes for causing a subdivision of the circulating medium and an independent regulated portion of the same to flow through said compartments at 125 130

- the same time without admixing with the atmosphere thereof, and means for varying the temperature of the circulating medium between 32 degrees Fahr. and 212 degrees Fahr. for the purpose of producing a warm or cold temperature as required in the various compartments.
4. The combination of two or more compartments, a radiating device in each compartment, a supply pipe and a return pipe leading to the several compartments and connected with the radiating devices, a tank communicating with the return pipe, a pump between the tank and supply pipe adapted to be used to reduce the pressure in the return pipe, a valved steam pipe connecting with the supply pipe, a valved passage between the return pipe and the pump, and means for permitting the pump to discharge outside of the supply pipe.
5. Apparatus for producing a great variation in temperatures in a plurality of independent compartments consisting of a separate temperature varying closed receptacle in each compartment, supply and return pipes leading to all of said temperature varying receptacles, circulating devices for causing a reduction of pressure below the pressure of the atmosphere in the return pipe and inducing a flow of the temperature producing medium through the supply pipe and simultaneously into the plurality of independent temperature varying closed receptacles, means for independently regulating the flow of said temperature producing medium into the respective receptacles, and means for varying the temperature of the circulating temperature producing medium between 32 degrees Fahr. and 212 degrees Fahr. for the purpose of producing a cold or warm temperature in the said receptacles to suit the temperature conditions required in the compartments.

In testimony of which invention, I hereunto set my hand.
